[57] CLAIM

The ornamental design for a flashlight battery recharger system, as shown and described.

DESCRIPTION

FIG. 1 is a front and lower right perspective view of a flashlight battery recharger system showing our new design, in which the broken line showing of the flashlight is included for the purpose of illustrating environmental elements only and forms no part of the claimed design;

FIG. 2 is a left side elevational view of a flashlight battery recharger system showing our new design on a slightly enlarged scale. The broken line showing is included for the purpose of illustrating environmental elements only and forms no part of the claimed design;

FIG. 3 is a front elevational view thereof;

FIG. 4 is a bottom plan view thereof;

FIG. 5 is a top plan view thereof; and,

FIG. 6 is a rear elevational view thereof.

FIG. 1.

FIG. 4.

Fig. 2.

Fig. 3.

FIG. 5.

FIG. 6.
